UNITED STATES PATENT OFFICE

CLIFTON BRIERLEY, OF PHILADELPHIA, PENNSYLVANIA, ASSIGNOR TO TASTY BAKING COMPANY, OF PHILADELPHIA, PENNSYLVANIA, A CORPORATION OF PENNSYLVANIA

SEPARATOR FOR CONTAINERS

Application filed March 23, 1929. Serial No. 349,473.

This invention relates to separators for containers and especially those containers in which merchandise is packed in two layers.

The object of my invention is to provide a novel, simple and inexpensive form of separator unit, which, when placed in the bottom of the container, functions to separate the individual articles of merchandise of the lower layer and also to partially separate the merchandise of the upper layer from the merchandise of the lower layer, a second separator unit being placed in the container above the first separator unit, the second unit functioning to complete the separation of the merchandise of the upper layer from the merchandise of the lower layer and also functioning to separate the individual articles of merchandise of the upper layer.

The construction of the separator unit made in accordance with the principles of my invention will be fully disclosed hereinafter, reference being had to the accompanying drawing, of which:

Fig. 1 is a perspective view of a typical form of container, adapted to receive two layers of merchandise;

Fig. 2 is a perspective view of a separator unit made in accordance with the principles of my invention, being shown in the position it assumes when employed in the lower layer;

Fig. 3 is a perspective view of a second separator unit of the same construction as the unit shown in Fig. 2, shown in the position it assumes when employed in the upper layer; and

Fig. 4 is a transverse sectional elevation of the container showing the two separator units in place and cooperating to separate the articles of merchandise of the upper layer from the articles of merchandise of the lower layer.

The container shown in Fig. 1 is of the collapsible type, being made from a single sheet of material and comprising a bottom 1, vertically extending end walls 2, 2, a front wall 3 and a back wall 4, all of which are formed integral with the bottom 1.

The back wall 4 is provided with a forwardly extending end flap 5 at each of its ends. The front wall 3 is provided at each

end with a rearwardly extending end flap 6. Each forwardly extending end flap 5 is provided with a slot 7 which is adapted to receive an ear 8 formed on the adjacent rearwardly extending end flap 6. By this means the elements of the container are locked together. 55 The rear wall 4 also has a cover 9 formed integral therewith. The end walls 2, 2 are provided with top flaps 10, 10, which when the container is packed are adapted to be folded inwardly. On the free edge of the cover 9 is a front flap 11 which is adapted to enter the container between the front wall 3 and the adjacent ends of the inturned flaps 10, 10.

The separator units shown in Figs. 2 and 65 3, each comprise a pair of longitudinal side members 15, 15^a, which are spaced apart by transverse partition members 16, 16. In the present instance, the partition members are each provided with lateral extensions 17, 70 which are secured to the side members 15, 15^a in any suitable manner, for example, by gluing.

The longitudinal side member 15^a of each separator unit is provided with a flap or shelf 75 member 20 which extends inwardly of and substantially half-way across the separator unit from the side member to which it is attached toward the other of the said side members, resting against the adjacent edges 80 of the transverse partition members 16, 16.

As shown in Fig. 4, the container and the pair of separator units, when the container is packed, maintain the same general relationship as that indicated in Figs. 1, 2 and 3. 85

In packing the container, one of the separator units is first placed in the container with the face having the flap 20 uppermost, the opposite face of the separator unit resting on the bottom 1.

The flap 20 is then turned up into a plane coincident with the plane of the longitudinal side member 15^a, to which it is attached. Articles of merchandise x , x are then placed in the compartments 25, 25^a formed between 95 the partitions 16, 16, and between the partitions 16, 16 and the adjacent end members 2, 2 of the container, thus forming the lower layer of merchandise in the container.

The flap 20 of the previously inserted sep- 100

arator unit is then turned down until it rests on the upper edges of the partitions 16, 16.

The second separator unit is then placed in the container with the flap 20 thereof down and toward the side of the container opposite to the side occupied by the flap 20 of the previously inserted separator, the said flap 20 of the newly inserted separator unit resting on the upper edges of the partitions 16, 16 10 of the previously inserted separator unit between the side member 15 and the free edge of the flap 20 of the said previously inserted separator unit.

In this manner the flaps 20, 20 of the respective separator units lie side by side and together form a shelf 30 which is adapted to support the merchandise of the upper layer and to separate the articles of merchandise of the upper layer from the articles of merchandise of the lower layer.

The articles of merchandise α are then placed in the compartments 25, 25^a of the upper separator unit.

In closing the container the front flap 11 of the cover 9 is inserted between the longitudinal side member 15 of the upper separator unit and the front wall 3 of the container.

Obviously the positions of the separator units may be reversed in the container by placing the units in the container with the shelf member or flap 20 of the lower unit adjacent the back wall 4 and the flap 20 of the upper unit adjacent the front wall 3, without departing from the spirit of the invention.

Obviously the separator unit may be made from a single piece of material, in place of several parts suitably secured together, for example, the longitudinal side member 15^a 40 and the shelf member 20 as in the present case could be integral and the flaps 17, and partitions 16 and the second side piece 15 could be made from a single strip integral with and extending from one end of the part 45 15^a; or the strip could be extended from both ends of the part 15^a, in the following succession, a part 17, a partition 16, and another part 17, with the part 15 extending therebeyond from either one or the other of the last 50 named parts 17, or partly from one of the last named parts 17 and partly from the other thereof, being suitably joined to complete the side member 15 when the separator is finished.

55 I claim:

1. A separator unit, for use in a container, comprising spaced side members, transverse members connecting said spaced side members and a shelf member extending part-way 60 across the separator unit from one of said side members toward the other thereof.

2. A separator unit, for use in a container, comprising spaced side members, transverse members connecting said spaced side members and a shelf member extending part-way 65

across one face of the separator unit from one of said side members toward the other thereof.

3. A separator unit, for use in a container, comprising spaced side members, a partition extending across said separator unit from one to the other of said side members, and a shelf member extending part-way across one face of the separator unit from one of said side members toward the other thereof.

4. A separator unit, for use in a container, comprising spaced side members, a plurality of spaced partitions extending across said separator unit from one to the other of said side members, and a shelf member extending part-way across one face of the separator unit from one of said side members toward the other thereof.

5. A separator unit, for use in a container, comprising spaced partition members, and a shelf member extending part-way across one face of the separator unit from a point substantially at the center of the unit to the ends of the partition members at one side of the unit.

6. A separator unit, for use in a container, comprising spaced partition members, a shelf member extending part-way across one face of the separator unit from a point substantially at the center of the unit to the ends of the partition members at one side of the unit, and a longitudinal member extending from one edge of the shelf member toward the opposite face of the unit.

7. The combination with a container having a bottom and side walls extending upwardly therefrom, of a pair of separator units each comprising a pair of side members respectively located adjacent a pair of oppositely disposed side walls of the container, and shelf members extending respectively part-way across the containers in opposite directions from one of the side members of each separator unit toward the other side member of the respective unit intermediate the bottom of the container and the top edges of the side walls thereof.

8. The combination with a container having a bottom and side walls extending upwardly therefrom, of a pair of separator units each comprising a pair of side members respectively located adjacent a pair of oppositely disposed side walls of the container, and shelf members extending respectively part-way across the containers in opposite directions from one of the side members of each separator unit toward the other side member of the respective unit intermediate the bottom of the container and the top edges of the side walls thereof and substantially parallel to the bottom of said container.

9. The combination with a container having a bottom and side walls extending upwardly therefrom, of a pair of separator units each comprising a pair of side members

respectively located adjacent a pair of oppositely disposed side walls of the container, a partition extending from one to the other of said side members, and shelf members extending respectively part-way across the containers in opposite directions from one of the side members of each separator unit toward the other side member of the respective unit intermediate the bottom of the container and the top edges of the side walls thereof.

10 10. The combination with a container having a bottom and side walls extending upwardly therefrom, of a pair of separator units each comprising a pair of side members respectively located adjacent a pair of oppositely disposed side walls of the container, a plurality of spaced partitions extending from one to the other of said side members, and shelf members extending respectively part-way across the containers in opposite directions from one of the side members of each separator unit toward the other side member of the respective unit intermediate the bottom of the container and the top edges of the side walls thereof.

25 11. The combination with a container having a bottom and side walls extending upwardly therefrom, of a pair of separator units, each of which comprises a partition extending substantially from one side wall of the container to an oppositely disposed side wall thereof, and a shelf member extending part-way across the container from one end of the partition toward the other end thereof, the shelf members of the pair of separator units being located in line with each other and extending from the said oppositely disposed walls of the container toward the center thereof and together forming a complete shelf disposed intermediate the bottom of the container and the top edges of the side walls thereof.

30 12. The combination with a container having a bottom and side walls extending upwardly therefrom, of a pair of separator units, each of which comprises a plurality of spaced partitions extending substantially from one side wall of the container to an oppositely disposed side wall thereof, and a shelf member extending part-way across the container from one end of the partition toward the other end thereof, the shelf members of the pair of separator units being located in line with each other and extending from the said oppositely disposed walls of the container toward the center thereof and together forming a complete shelf disposed intermediate the bottom of the container and the top edges of the side walls thereof.

35 13. The combination with a container having a bottom and side walls extending upwardly therefrom, of a pair of separator units, each of which comprises a plurality of spaced partitions extending substantially

from one side wall of the container to an oppositely disposed side wall thereof, a shelf member extending part-way across the container from one end of the partition toward the other end thereof, the shelf members of the pair of separator units being located in line with each other and extending from the said oppositely disposed walls of the container toward the center thereof and together forming a complete shelf disposed intermediate the bottom of the container and the top edges of the side walls thereof, and a longitudinal member extending from one edge of the shelf member of each unit in a plane substantially perpendicular to that of said shelf member and substantially at right angles to the partitions.
